(57) **ABSTRACT**

A new garden rose plant of the Miniature class which has abundant, white flowers and attractive foliage. This new and distinct variety has shown to be uniform and stable in the resulting generations from asexual propagation.

2 Drawing Sheets

1

Botanical designation: *Rosa hybrida*.
Variety denomination: 'Poulpah099'.

SUMMARY OF THE INVENTION

The present invention constitutes a new and distinct variety of rose plant which originated from a controlled crossing between the female seed parent, an unnamed seedling, and the male pollen parent, also an unnamed seedling. Both of the parent varieties are non-patented.

The two parents were crossed during the summer of 2011 and the resulting seeds were planted in a controlled environment in Fredensborg, Denmark. The new variety, named 'Poulpah099', originated as a single seedling from the stated cross.

The new variety may be distinguished from its male pollen parent and female seed parent primarily by the following characteristics. The male pollen parent plant has near white flowers with a diameter of 50 mm while the new variety has white flowers with a diameter of 65 mm. The female seed parent plant has russet tan flowers while the new variety has white flowers.

The objective of the hybridization of this rose variety was to create a new and distinct variety with unique qualities, such as:

1. Uniform and abundant white flowers;
2. Vigorous, but compact growth when propagated on its own roots;
3. Exceptional disease resistance.

This combination of qualities is not present in previously available commercial cultivars of this type, known to the inventor, and distinguish 'Poulpah099' from all other varieties of which we are aware.

As part of the rose development program, Mogens N. Olesen germinated the seeds from the aforementioned

2

hybridization during winter of 2011 and conducted evaluations on the resulting seedlings in a controlled environment in Fredensborg, Denmark. 'Poulpah099' was selected in the spring of 2012 by the inventor as a single plant from the progeny of the aforementioned hybridization.

Asexual reproduction of 'Poulpah099' by rooted cuttings was first done by Mogens N. Olesen in the nursery in Fredensborg, Denmark in July, 2012. This initial and other subsequent asexual propagations conducted in controlled environments have demonstrated that the characteristics of 'Poulpah099' are true to type and are transmitted from one generation to the next.

DESCRIPTION OF THE DRAWING

The accompanying color illustrations show as true as is reasonably possible to obtain in color photographs of this type, the typical characteristics of the buds, flowers, leaves, and stems, of 'Poulpah099'.

Specifically illustrated in FIG. 1 of the drawings are open flowers viewed from the side and above, flower petals detached revealing the receptacle and reproductive flower parts, and detached sepals.

Specifically illustrated in FIG. 2 of the drawings are bare stem and mature leaves. Plants shown are 4 months of age.

DETAILED DESCRIPTION OF THE VARIETY

The following is a description of 'Poulpah099', as observed in its growth in a controlled environment greenhouse in Odense Denmark. Observed plants are 4 months old and were grown on their own roots in 19 cm containers. Color references are made using The Royal Horticultural Society (London, England) Colour Chart, 2001, except where common terms of color are used.

For a comparison, several physical characteristics of the rose variety 'Poulpah059', U.S. Plant Pat. No. 24,850 are compared to 'Poulpah099' in Chart 1.

CHART 1

	'Poulpah099'	'Poulpah059'
Petal Count	65	50
Flower Diameter	65 mm	75 mm
General Tonality of Flower Color	Open flowers are Yellow-White Group 158C	Orange Group 25A and Yellow Group 11C

FLOWER AND FLOWER BUD

Blooming habit: Continuous.
Flower bud:

Size.—Upon opening, 19 mm in length from base of receptacle to end of bud. Bud diameter is 15 mm.

Bud form.—Ovoid.

Sepal inner surface.—Color: Yellow-Green Group 146D. Surface: Lightly pubescent.

Sepal outer surface.—Color: Yellow-Green Group 144A. Texture: Smooth.

Sepal shape.—Apex: Cirrhose. Base: Flat at union with receptacle.

Sepal margin.—Margins have moderate foliaceous appendages on three of the five sepals.

Sepal size.—19 mm long, 9 mm wide.

Receptacle.—Texture: Smooth. Size: 5 mm in height, 9 mm wide. Color: Yellow-Green Group 144A. Shape: Funnel.

Pedicel.—Surface: Smooth. Length: About 56 mm. Diameter: 3 mm on average. Color: Yellow-Green Group 144A. Strength: Strong.

Flower bud development: Flower buds are borne single or in clusters of 3 to 5 flower buds per stem.

Flower bloom:

Fragrance.—Strong perfume.

Duration.—The blooms have a duration on the plant of approximately 19 days. Petals fall cleanly away from plant after flowers have fully matured.

Size.—Flower diameter is 65 mm when open. Flower depth is 45 mm.

Flower shape.—Globular.

Shape of flower, side view.—The upper portion is rounded. The lower portion is concave.

Petalage: Under normal conditions, flowers have about 65 petals.

General tonality of flower: Open flowers are Yellow-White Group 158C.

Petal color:

Upon opening, outer petals.—Upper surface: White Group 155C. Lower surface: White Group 155B with intonations of Yellow-Green Group 145D.

Upon opening, inner petals.—Upper surface: White Group 155B with intonations of Yellow White 158C. Lower surface: White Group 155B.

Basal petal spots.—No distinctive coloration at the petal base observed.

After opening.—Petal colors remain the same.

Petals:

Petal reflex.—Moderate reflex at the margin.

Margin.—Entire and uniform. No undulation.

Shape.—Rounded. Apex shape: Rounded. Base shape: Rounded.

Size.—34 mm (l)×30 mm (w).

Texture.—Smooth.

Thickness.—Average.

Reproductive flower parts:

Pollen.—None observed.

Anthers.—Size: 2 mm in length. Color: Greyed-Yellow Group 162B. Quantity: 35 on average.

Filaments.—Color: White Group 155A. Length: 4 mm.

Pistils.—Length: 10 mm. Quantity: 28 on average.

Stigmas.—Color: Yellow-Green Group 150D.

Styles.—Color: Yellow-Green Group 145D.

Location of stigmas.—Level in location relative to the length of the filaments and the height of the anthers.

Hips.—None Observed.

PLANT

Plant growth: Upright. Plants are 50 cm in height, and 40 cm wide.

Stems:

Color of juvenile growth.—Yellow-Green Group 144B.

Color of mature growth.—Yellow-Green Group 144A.

Length.—Canes are about 36 cm from the base of the plant to the flowering portion.

Diameter.—About 6 mm.

Internodes.—On mature canes about 28 mm between nodes.

Surface texture.—Young wood: Smooth. Older wood: Smooth.

Long prickles:

Incidence.—4 prickles per 10 cm of stem.

Size.—Average length of prickles on mature stems is 6 mm.

Shape.—Upper portion is linear. Lower portion is concave.

Color.—Juvenile prickles: Greyed-Yellow Group 162B. Mature prickles: Greyed-Yellow Group 162B with intonations of Greyed-Red Group 179B.

Plant foliage:

Compound leaf.—About 115 mm (l)×100 (w).

Quantity.—Usually 3 leaves per 10 cm of stem.

Leaf bearing angle to the stem.—45 degrees.

Color of juvenile foliage.—Upper side: Yellow-Green Group 144A. Lower side: Yellow-Green Group 144B.

Color of mature foliage.—Upper side: Yellow-Green Group 146A. Lower side: Yellow-Green Group 147C.

Plant leaves and leaflets:

Stipules.—Size: 17 mm long, mm wide. Quantity: 2 per compound leaf. Shape: Linear, slightly broad based with outward extending apices. Margins: Finely serrated. Color:

Petiole.—Length: 21 mm. Diameter: 2 mm. Upper surface color: Yellow-Green Group 144A. Lower surface color: Yellow-Green Group 144A.

Rachis.—Length: About 30 mm. Upper surface color: Yellow-Green Group 144A. Lower surface color: Yellow-Green Group 144A.

Leaflet.—Quantity: Normally 5 leaflets. Margins: Serrated. Size: Terminal leaflets are about 57 mm long, 38 mm wide. Shape: Generally elliptical. Base: Rounded. Apex: Acute. Texture: Smooth. Thickness:

US PP32,893 P2

5

Average. Arrangement: Odd pinnate. Venation:
Reticulate. Glossiness: Not glossy.

Disease resistance: Above average resistance to powdery
mildew *Sphaerotheca pannosa* var. *rosae*, downy mildew
Peronospora sparsa, rust *Phragmidium* spp., black spot
Diplocarpon rosae, and *Botrytis cinerea* under normal
growing conditions.

Cold hardiness: The variety is tolerant to USDA Cold
Hardiness Zone 6.

6

Heat tolerance: The variety has been found to be suitable for
climate conditions found in the American Horticulture
Society heat zone 7.

I claim:

5 1. A new and distinct variety of rose plant of the Miniature
rose class named 'Poulpah099', substantially as illustrated
and described herein, due to its abundant white flowers,
disease resistance, and extended period of bloom.
